US0D1024064S

(12) **United States Design Patent** (10) **Patent No.:** **US D1,024,064 S**
(45) **Date of Patent:** **** Apr. 23, 2024**

(54) **DATA PROCESSING READER**

(71) Applicant: **NEXTVPU (SHANGHAI) CO., LTD.**,
Shanghai (CN)

(72) Inventors: **Zhijun Lv**, Shanghai (CN); **Yin Tang**,
Shanghai (CN); **Haijiao Cai**, Shanghai (CN);
Xinpeng Feng, Shanghai (CN);
Ji Zhou, Shanghai (CN)

(**) Term: **15 Years**

(21) Appl. No.: **35/516,129**

(22) Filed: **Sep. 16, 2022**

(80) **Hague Agreement Data**

Int. Filing Date: **Sep. 16, 2022**

Int. Reg. No.: **DM/226082**

Int. Reg. Date: **Sep. 16, 2022**

Int. Reg. Pub. Date: **Jan. 27, 2023**

(51) **LOC (14) Cl.** **14-02**

(52) **U.S. Cl.**

USPC **D14/358**

(58) **Field of Classification Search**

USPC D14/160, 172, 183–184, 196, 203.1, 204,
D14/207, 302, 348–349, 351–352,
D14/356–359, 363, 368; D21/324,
D21/513–515

CPC G10K 15/04; H04R 1/02; G06F 3/16
See application file for complete search history.

Primary Examiner — Joshua Kading
Assistant Examiner — Altaira J Swangin

(57) **CLAIM**

The ornamental design for a data processing reader, as shown and described.

DESCRIPTION

- 1.1: Front
- 1.2: Rear
- 1.3: Left
- 1.4: Right
- 1.5: Top
- 1.6: Bottom
- 1.7: Front Right Perspective
- 1.8: Front Right Perspective in an alternate configuration of use
- 2.1: Front in another alternate configuration of use
- 2.2: Back
- 2.3: Left
- 2.4: Right
- 2.5: Top
- 2.6: Bottom
- 2.7: Front Right Perspective
- 2.8: Back Left Perspective
- 2.9: Back Perspective
- 2.10: Front Right Perspective in another configuration of use

1 Claim, 18 Drawing Sheets
